H. BRUBAKER.
HYDROCARBON BURNER.
APPLICATION FILED NOV. 8, 1916.

1,233,547.

Patented July 17, 1917.

UNITED STATES PATENT OFFICE.

HENRY BRUBAKER, OF YORK, PENNSYLVANIA, ASSIGNOR TO W. C. KOLLER, OF YORK, PENNSYLVANIA.

HYDROCARBON-BURNER.

1,233,547.

Specification of Letters Patent.

Patented July 17, 1917.

Application filed November 8, 1916. Serial No. 130,177.

To all whom it may concern:

Be it known that I, HENRY BRUBAKER, a citizen of the United States, residing at York, in the county of York and State of Pennsylvania, have invented certain new and useful Improvements in Hydrocarbon-Burners, of which the following is a specification, reference being had therein to the accompanying drawings.

10 My invention relates to improvements in hydrocarbon burners.

The objects of the invention are to provide a burner, preferably of the multiple burner-head type, which may be quickly set up and dismantled; in which the feed of hydrocarbon to each burner head may be controlled manually so that the degree of heat can be regulated to a nicety; to provide heat deflectors which may be thrown 20 into or out of operative relation with the source of heat, and to provide a settling chamber which will collect dirt and other foreign matter, and prevent its passage to the main burner heads.

25 To the accomplishment of the recited objects and others coördinate therewith, the preferred embodiment of my invention resides in the construction and arrangement hereinafter described, illustrated in the accompanying drawings and embraced within the scope of the appended claims.

In said drawings:

Figure 1 is a perspective view of the burner installed in a cooking stove.

35 Fig. 2 is a perspective view of burner detached, and partly broken away to show the inner working parts.

Fig. 3 is a perspective view of the bottom of the base of the burner.

40 Fig. 4 is a transverse sectional view taken along lines 4—4 of Fig. 2, and

Fig. 5 is a vertical sectional view of the settling chamber.

In the drawings, 5 designates generally 45 the base of the burner, which comprises a housing 6 and a drip-pan 7. The housing is divided into two terminal compartments 8 and 9, each provided with a flame opening 10, and said housing further having an intermediate central opening 11. The vertical partition 12 between each of the compartments and the central opening has a re-

cess 13 at its lower edge. The function of the opening 11 and the recesses 13 will presently appear.

Specifically, the burner consists of a pair of oppositely disposed overlying retorts 14 and 15 connected with any suitable head of hydrocarbon by means of the pipe 16. The adjacent terminals of the retorts communicate with a central settling chamber 17, which has a depending connection 18, with a pair of burner-heads 19 and 20, having the usual orifices 21 arranged medially in vertical alinement with the flame openings 10. 65 All of the various parts of the burner just described are formed from short lengths of pipe which may be easily obtained at a very low figure, and when set up, constitute a composite one piece structure.

Upon again referring to the housing 6, and particularly with reference to Fig. 4 of the drawings, it will be seen that the casting is formed with upwardly converging walls 22. The outer edges of the drip pan 7 are 75 similarly inclined, as at 23. Now in the organization of the device, the burner heads 19 and 20 are received by the recesses 13, and the remaining portion of the burner, including the settling chamber and retorts, 80 is connected to the burner heads by the depending connection 18. The drip pan is then inserted in the base and the vertical bolts 24 tightened. This operation wedges the pan with respect to the base, and simultaneously wedges the burner heads relative to the recesses 13, thereby firmly anchoring the burner in proper position below and above the said base. In order to provide for complete combustion air is admitted 90 through the openings 25 in the drip pan.

In the burners which I have observed there has been no practical provision made for controlling the degree of heat emitted by the burners. Either all of the burner heads 95 are, or are not in operation at the same time. When all of the burner-heads are afame, the heat generated is frequently so intense that the burner is actually burned out, or in any event, the heat is greater than desired for 100 ordinary heating or cooking purposes. I eliminate this disadvantage by the addition of a very simple valve mechanism coöperating with the orifices in the burner-heads,

whereby any desired number of burner-heads may be controlled. As will be found upon inspection of Figs. 2 and 4, I fasten a bracket 26, by means of nuts 27, to the rear wall of each compartment, said bracket having one end of a lever 28 loosely pivoted thereto, while the other end of said lever projects through an L slot 29 in the opposite wall of the compartment and within easy reach of the attendant. Depending from the lever is a small valve 30 which is designed to close the orifice 21. It will be seen that by elevating the lever and allowing it to seat upon the highest portion of the slot, as exhibited in full lines in Fig. 4, the orifice will be uncovered; and that by lowering the lever, in the vertical portion of the slot, as shown in dotted lines, the orifice will be closed. Either or both of the burner heads 20 may therefore be controlled at will.

The flame deflectors 31 are longitudinally and rotatably adjustable with respect to the retorts, and in vertical positions may be wedged against the reduced lateral extensions 32 of the settling chamber to temporarily hold them out of the path of the flames.

Another extremely important feature of my invention is the construction of the settling chamber 17, common to both retorts. Upon inspection of Fig. 5 it will be seen that a stand-pipe 33 is arranged concentrically within the chamber 17 in communication with the connection 18 and terminates at its upper end just short of the closure 34. It follows that the combustible gas entering from the retorts must first pass upwardly between the adjacent walls of the chamber 17 and the stand-pipe 33, and then downwardly through the latter to the burners. Carbon, dirt, and other foreign particles which may be held in suspension in the combustible gas will obviously settle in the chamber and thus be prevented from finding their way to the burner heads and clogging up the orifices. The settling chamber may

be cleaned whenever the occasion requires by removing the closure 34.

What is claimed is:

1. In a hydrocarbon burner, the combination of a base having slotted partitions, a drip-pan, a burner head adapted to be received in the slots of said partitions, and means connected to the base and the drip-pan whereby the latter is clamped against said burner head. 50

2. In a hydrocarbon burner, the combination of a base provided with partitions, a burner head, a drip-pan, and means for clamping said burner head between the partitions and the drip-pan. 60

3. In a hydrocarbon burner, the combination of a base having converging side walls and a plurality of vertical partitions, a wedge-shaped bottom for the base, a burner head between the lower end of the partitions and the bottom, and means for fastening the base and bottom together. 65

4. In a hydrocarbon burner, the combination of a base having converging side walls and a plurality of partitions extending downwardly and terminating short of the bottom of said base, a wedge-shaped drip-pan adapted to be inserted in the bottom of the base, a burner head between the partitions and the drip-pan, and means for clamping the burner head therebetween. 70 75

5. In a hydrocarbon burner, the combination with a housing and a burner head having an opening therein, of a support carried by said housing, a lever loosely pivoted to said support and capable of movement in two different planes, and a valve mounted upon said lever for coöperation with said opening. 80

In testimony whereof, I hereunto affix my signature, in the presence of two witnesses.

HENRY BRUBAKER.
